MICROTOME SHAVER TRAP

Warren Drake, 1205 Langdon Blvd., Rockville Centre,
N.Y. 11570, and Jack R. Scheel, 35 Candle Lane,
Levittown, N.Y. 11756

Filed Nov. 11, 1974, Ser. No. 522,510

Term of patent 14 years

Int. Cl. D24—01

U.S. Cl. D32—2 C

FIG. 1

FIG. 2

FIG. 3

FIG. 5

FIG. 4

FIG. 6

FIG. 8

FIG. 9

FIG. 10

FIG. 7

FIG. 11

FIG. 12

FIG. 1 is a perspective view of a microtome shaver tray showing our new design;

FIG. 2 is a top plan view thereof;

FIG. 3 is a front elevational view thereof;

FIG. 4 is a bottom plan view thereof;

FIG. 5 is a side elevational view thereof;

FIG. 6 is a rear elevational view thereof;

FIG. 7 is a perspective view of a microtome shaver trap showing a second embodiment of our new design;

FIG. 8 is a top plan view of FIG. 7;

FIG. 9 is a front elevational view of FIG. 7;

FIG. 10 is a bottom plan view of FIG. 7;

FIG. 11 is a side elevational view of FIG. 7; and

FIG. 12 is a rear elevational view of FIG. 7.

We claim:

The ornamental design for a microtome shaver trap, as shown and described.
